A.M. Carlsen

UNITED STATES PATENT OFFICE.

BERNARD T. PENNIG, OF ST. PAUL, MINNESOTA, ASSIGNOR TO PENN-GREG MFG. CO., OF ST. PAUL, MINNESOTA, A COPARTNERSHIP CONSISTING OF JOEL E. GREGORY, ESTHER SOPHIA STRAND, AND HIMSELF.

MAIL BOX IN HOUSE WALLS.

1,423,251.

Specification of Letters Patent. Patented July 18, 1922.

Application filed February 7, 1920. Serial No. 356,820.

To all whom it may concern:

Be it known that I, BERNARD T. PENNIG, a citizen of the United States, residing at St. Paul, in the county of Ramsey and State 5 of Minnesota, have invented a new and useful Mail Box in House Walls, of which the following is a specification.

My invention relates to mail boxes at 10 residences and offices; and the object is to provide a mail box concealed in any suitable part of a wall of a building where it will expose the mail dropped in the box by the mail carrier to the occupants of the house and be there within easy reach without 15 going out of the house to see if any mail has arrived.

With this and other objects in view the invention consists of the parts and arrangements illustrated in the accompanying 20 drawing in which:

Fig. 1 is an elevation of the door and frame through which the mail is delivered into a building and the adjacent portion of the wall of the building. Fig. 2 is an elevation of the frame and door and adjacent portion of the inner side of the wall of a building at the point where the mail is received into the room. Fig. 3 is a vertical section as on the line 3—3 in Figures 1 25 and 2.

Referring to the drawing by reference numerals, 4 designates the studdings, 5 the lath, 6 the plastering, 7 the sheeting and 8 the siding of a house wall in which my 30 improved mail box is inserted.

9 is the mail box proper and is preferably made of galvanized sheet iron. It constitutes a vertically elongated pocket say about eighteen inches deep, seven inches wide and 40 practically filling between the sheeting and the lath of an ordinary house wall. The box is secured by screws 10—11 to brackets 12, 13 fixed to the sheeting. It is also soldered or otherwise secured to metal frames 14 and 15, 45 which are "roughed in" into the wall during its erection, and have finishing door frames afterward secured to them.

The lower end of the box has an incline 16 and in its bottom 17 apertures 18 to allow circulation of air and to prevent accumulation of dirt in the box. 19 and 20 are inclined guards designed to prevent stealing of the mail by the so-called wire and gum thieves.

Secured to the frame 15 by screws 21 is 55 a door frame 22, to which a door 23 is hinged at 24 and provided with a suitable catch 25 for holding it closed. Said door may preferably have a glass panel 26 through which to see if there is mail in the 60 box without opening the door.

The frame 14 is formed with sockets 27, into which project from a door frame 28 studs 29, which are secured in said sockets by screws 30 having their heads within the 65 mail box. In the frame 28 is hinged by concealed pintles 31 a lid or door 32, having a weight 33 to hold it normally closed with its rabbeted edge 34 against the lower edge 35 of the frame 28. When the door is thus 70 closed its lower edge 36 projects slightly outward beyond the frame so as to guide away rain water if the door happens to be exposed to a rain storm. If the frame 28 in some rare case is much exposed to rain it 75 may also be protected by a cap 37 fixed close above it.

The screws 30 are inserted by a hand reached upwardly through the box from the door frame 15 and can thus not be reached 80 and removed through the door frame 28.

When letters or cards or similar articles are dropped into the box they will lean against the inclined face 16 so as not to be crushed or unduly bent by heavier or harder 85 articles like magazines, merchandise or the like. The incline or bevel 16 also tends to make it impossible for persons to take out letters from outside by means of wires or gum sticks.

From the above description it will be understood that I provide a mail box which may be inserted in any convenient place in a wall either during the erection of a house or by proper operation any time after the 90 house is built. As the box is not in the door of the house nor necessarily near the door it is invisible from the street. The box may also be made large enough to hold the mail for several days if the owner happens 95 to be absent.

In depositing the mail the mail carrier simply presses or pushes the door 32 open and drops the mail in, and he thereby places the mail in sight of the owner so that the 100 latter cannot easily overlook it for any length of time, as is often the case with mail boxes which do not display the mail

to the inside of the house, but rather to the outside, where it tempts mail thieves and is not noticed by the owner when he leaves the house or returns home in the dark.

5. What I claim is:

1. The combination with double walls, of a mail box mounted between said walls and covered thereby, and an anchoring bracket secured to the mail box and one of the walls 10 on the inside thereof, one of said walls and the mail box having coincident inlet openings and the other of said walls and mail box having coincident outlet openings.

2. The combination with double walls, of 15 a mail box mounted between said walls and covered thereby, one of said walls and the mail box having coincident inlet openings and the other of said walls and mail box having coincident outlet openings, said mail 20 box having at its openings marginal frames extending into the openings in the walls.

3. The combination with double walls, of 25 a sheet metal mail box mounted between said walls and covered thereby, one of said walls and the mail box having coincident inlet openings and the other of said walls and the mail box having coincident outlet openings, marginal frames for the openings in the mail 30 box extending into the openings in the walls, and means securing one of the marginal frames to the mail box from the inside thereof.

4. A mail box having an inlet opening in 35 one of its sides and an outlet opening in its other side, said openings being vertically spaced the one above the other and the latter being vertically spaced above the bottom of

the mail box, a downwardly inclined guard on the side of the mail box having the inlet opening and located between said openings, 40 and a downwardly inclined guard on the side of the mail box having the outlet opening and located therebelow.

5. A mail box having in one of its sides 45 an inlet opening and an outlet opening in its other side, said openings being vertically spaced the one above the other and the latter being vertically spaced above the bottom of the mail box, a downwardly inclined guard on the side of the mail box having the inlet 50 opening and located between said openings, and a downwardly inclined guard on the side of the mail box having an outlet opening and located therebelow, the bottom of the mail box at the side thereof having the inlet opening being downwardly inclined and the other side thereof being horizontal.

6. A mail box having in one of its sides 55 an inlet opening and in its other side an outlet opening, said openings being vertically spaced the one above the other, said outlet opening being vertically spaced above the bottom of the mail box, a downwardly inclined guard on the side of the mail box having the inlet opening and located between 60 said openings, and a downwardly inclined guard on the side of the mail box having the outlet opening and located therebelow, the bottom of the mail box at the side thereof having the inlet opening being downwardly inclined and the other side thereof being horizontal.

In testimony whereof I affix my signature.

BERNARD T. PENNIG
